tion of Delaware

Filed Dec. 28, 1961, Ser. No. 162,669
14 Claims. (Cl. 107—14)

This invention relates to a die structure for a wafering machine and particularly for that type of machine used for wafering forage products such as hay, grasses, straw and the like.

In a machine of this type, as distinguished from the conventional so-called pellet mill, which is primarily intended for the handling of granular or pulverulent material, one of the major problems during the field operation is incurred in the change-over from a single row of die cells or openings to a multiple row. That is to say, as distinguished from the conventional pellet mill, the die means in a wafering machine, which is conventionally or preferably annular, is made up of an annulus comprising a pair of ring-like coaxially spaced apart side members and a plurality of uniformly circumferentially spaced apart intervening die blocks or spacers which afford a like plurality of generally radially extending die openings, which in common practice to date are rectangular in section so that the machine is capable of producing wafers in the form of products having a cross-section of two inches by two inches and varying in length from three to six inches, for example, depending upon the length of each die opening and depending further upon the type of means used for breaking the wafer off after it is extruded. The interior periphery of the annulus, in the usual case, affords a track at which the inlet ends of the die openings lead so that an orbiting press wheel or 35 wheels within the annulus rolls about the track and successively extrudes forage material through the die openings. In most cases, the annulus will be fixed and the orbiting action of the press wheel may be regarded as planetary. In other instances, both the annulus and the press wheel move, which is largely a matter of choice, at least so far as the present invention is concerned.

It is desirable in some instances to produce wafers having a smaller cross section than that noted above, and some effort has been devoted to the production of an annulus in which a splitter means is used laterally intermediate the side members so that the two-by-two inch wafers are in effect split into two-by-one inch wafers (less the thickness of the splitter). However, most of these change-overs require considerable dismantling of the annulus, which is normally of a fabricated structure in which at least one of the side members can be removed. In some instances, the conversion from a single-row to a multiple-row die also requires interchangeability of the blocks to accommodate the splitter means.

According to the present invention, these problems are eliminated by the provision of a die annulus in which a splitter is utilized in the form of a continuous circumferential member readily mounted in and readily removable from the basic annulus so as to be readily installed and removed in the field without dismantling of the major parts of the machine. In a preferred embodiment of the invention, the divider element is in the form of a wire-like or rod-like element which may be of circular, rectangular, etc. section or such other element which extends circumferentially and circumscribes or is circumscribed by the circle on which the inlet ends of the die openings lie. It is a feature of the invention to provide novel retaining means for holding the divider element in place. In one form of the invention, the inner ends of the spacers are notched so as to receive the divider, which may be

2

in the form of a snap ring having such resilience that its diameter may be changed for insertion and removal, it being understood that, because of its snap ring characteristics, the bias in the ring normally maintains it in place.

5 In another form of the invention, the inner ends of the spacers are circumferentially apertured in circumferential alignment and the divider is threaded therethrough. The divider, when installed, is continuous, but of course it is provided in its snap-ring form with separated ends, and in 10 one form of the invention these ends are so shaped as to establish an overlap and interlock retainable within the aperture of one of the die openings. Fundamentally, the divider element has limited cross-sectional area or dimension in the direction of movement of the wafered material and, being installed at the inlet ends of the die openings, causes the material to split at the inlet end and, even though the material merges beyond the divider, it is found that the two (or more) separated sections of the wafer can be readily separated, thus enabling 15 handling of the wafers in smaller sizes. The significance of using the splitter means at the inlet end of the die cell is that in that area the material is still somewhat "plastic" or free-flowing or "softer" and hence is easier to split than it would be farther up in the cell, where it would 20 be harder and more compact. Further, according to this invention, splitting into two or more cells can be achieved 25 without applying density control to the splitting means.

The foregoing and other important objects and desirable features inherent in and encompassed by the invention will become apparent as a preferred embodiment thereof is disclosed in detail in the ensuing description and accompanying sheet of drawings, the figures of which are described below.

FIG. 1 is a perspective of a representative die annulus.

FIG. 2 is a reduced elevation, partly in section, and with parts broken away, showing a typical relationship between the annulus and a press wheel for extruding material radially outwardly through the die openings.

FIG. 3 is an enlarged fragmentary section of substantially the broken-away portion shown in FIG. 2, illustrating one form of the invention.

FIG. 4 is an enlarged section on the line 4—4 of FIG. 1, but to which has been added a representative formation of a split wafer plus the association of the press wheel relative to the die opening.

FIG. 5 is a view similar to FIG. 3 but showing a variation in the divider element structure.

In the preferred structure illustrated, the die annulus, designated in its entirety by the numeral 10, is generally 50 fixedly mounted in a framework (not shown) and is made up of coaxially spaced apart ring-like side members 12 and 14, the latter having an inside diameter smaller than that of the former. Rigidly secured between the side members, in any suitable fashion, as by a plurality of bolts 16, is a plurality of uniformly circumferentially spaced and generally radially arranged spacers or die blocks 18, which consequently afford a like plurality of die cells or openings 20. In the particular 55 instance chosen for purposes of illustration, the inner ends of the spacers, as at 22 coincide generally with what may be regarded as a "circle" about the axis of the annulus, and this circle has a diameter somewhat larger than the inside diameter of the member or circular plate 12 (FIG. 4) thus affording a track or groove in the general area 60 designated 24 in or substantially in which a press wheel 26 rolls as it is carried in orbital or planetary fashion in a circular path traveled by its axis here represented by a press wheel shaft 28 which may be part of a crank shaft journaled in the framework (not shown) and having its main axis coincident with the axis of the annulus, as shown at 39. For example, and looking at

FIG. 2, the crank shaft 28 may turn about the axis 30 in a counterclockwise direction, and the press wheel 26 will of course turn in a clockwise direction about the axis of the wheel shaft 28 as it rolls about the die track. These characteristics are fundamentals to those versed in the art and are referred to here largely for purposes of environment and to establish that the ends of the die openings, as at 32, at one periphery of the die are the inlet ends, and the opposite ends, as at 34, are the outlet ends at the opposite periphery of the die. Thus, material engaged by the press wheel 26 on the "track" 24 will be extruded successively into and through the die openings, to be discharged radially outwardly. However, the particular direction of material movement is not a limitation for instances are known in which a press wheel will travel on the outer track of the annulus, or two similar annuli will be run rim-to-rim for the same purpose (see U.S. Patent 3,052,192); consequently, such expressions as "inner," "inlet," etc. are used only representatively and not by way of limitation. Hence, these details form no part of the present invention and are mentioned only by way of explanation that variations therein do not materially affect the exploitation of the invention.

From the description so far, it will be seen that material extruded through the die openings 20 exits therefrom as extrusion products in the form of wafers having the cross-sectional shape of each die opening, which is here rectangular and which may be on the order of two by two inches or two by two and one-half inches, etc., 25 two depending upon individual requirements. On the other hand, it is often desirable to split the cross-sectional area of the wafer so that one or more wafers is discharged through each die opening. In the present instance, a splitting system involving a central division of the row 35 of die openings is disclosed, but it will be clear that any number of divisions may be utilized consistent with the over-all results obtainable.

In that form of the invention shown in FIGS. 1-4, the division or divider element is shown as an element 36 of wire-like or rod-like nature; at any rate, having a limited radial dimension compared to the radial length of a die cell or opening 20, as distinguished from the plate-like splitters that have been used in prior machines. The element, hereinafter referred to as a wire, as a means for description but not limitation, extends circumferentially about the inner periphery of the annulus as represented by the track 24, it being understood that the annulus of course has an outer periphery represented by the outer ends of the blocks 18. The wire is arranged, in the present instance, at the inlet ends of the openings and retaining means is provided, cooperative between the inner ends of the blocks 18 and the wire, for retaining the wire in place, and, as will be seen, this retaining means is so constructed that the wire may be readily installed and removed. In that form of the invention shown in FIGS. 1 through 4, the inner end 22 of each block 18 is provided with a gap or notch 38, which notches extend circumferentially of the annulus and, in this instance, the circumferential line of notches is located midway between the inner surfaces of the side members or plates 12 and 14. The arrangement would be otherwise if the division of the wafers was greater than two. Nevertheless, the wire 36 is formed as a snap-ring, or at least has snap-ring characteristics, to the extent that it is resilient so that it is capable of having its diameter temporarily distorted and subsequently restored so that when it is installed it can be readily slipped into the notches 38. It is preferred that the meeting ends of the wire, as at 40, be located within the notch 38 of one of the blocks 18. The effect on the material forced through the associated die opening 20 is illustrated schematically in FIG. 4, wherein it will be seen that the intervening wire 36, which circumferentially bridges the inlet end 32 of the die opening, causes the material to

split into two paths. Even though the material merges along the ultimate path, as along the line 42, there will be two easily separable wafers as at 44 and 46, the result being that these can be forcibly separated or in some instances will separate by themselves when they are ultimately handled by whatever material-transfer system is used with the machine.

In the modified form of the invention as shown in FIG. 5, the annulus has substantially the same structure except that die blocks, designated here at 18', but otherwise having the same locational characteristics as the blocks 18 so as to afford die openings 20', have their inner ends 22' provided with a different form of opening, in this case comprising a series of circumferentially directed and aligned apertures 38' in which a wire-like or rod-like divider element 36' is threaded. The ends of the wire 36' which meet after installation is complete may be overlapped and shaped to interfit as shown at 40', and the location of the interlock is preferably such that it is confined within one of the apertures 38'. When it is desired to remove the wire 36', it may be circumferentially shifted to expose the interlock, after which the wire may be drawn out of the apertures 38', following separation of the interlock. In many instances, the low cost of the wire will be such that it will be feasible to cut the wire at opportune locations and discard it, ultimately replacing it with another. The same applies to the snap-ring wire 36 of FIGS. 1 through 4. The operational characteristics of the wire 38' as a divider will follow those illustrated in FIG. 4 and described in connection with the wire 36.

In FIG. 4, the wall 34 is shown as the inner surface of a density control blade 50, here recessed in the wall 12 to pivot at 52. An annular manifold 54, made up of a plurality of cylinders 56, one for each die cell, each having a piston 58 pushing via a piston rod 60 on the associated blade 50, is mounted on the wall 12. The cylinders 56 are connected in parallel by a fluid passage 62. This is a representative construction, the basic principle of which forms the subject matter of assignee's copending application by Firth Ser. No. 66,874 filed November 2, 1960. Any other type of density control may be used, suffice it to say here that the splitter 36 (36') or several of them, may be used without the addition of further intermediate density control blades. In other words, forces applied to the material in the cell by the single blade 50 will be sufficient for both wafers 44 and 46 (or more wafers if more splitters are used).

As already stated, the arrangement may be such that more than one wire may be used to divide the die openings into more than two smaller cells or openings. These, as well as other characteristics which will readily occur on the basis of the present disclosure, will be readily achieved by those versed in the art, all without departure from the spirit and scope of the invention.

What is claimed is:

1. Die structure for a wafering machine, comprising: an annulus having inner and outer peripheries and including a pair of coaxially spaced apart ring-like side members and a plurality of uniformly circumferentially spaced apart generally radial spacers arranged between the side members and rigid therewith to provide a like plurality of die openings, each spacer and opening having radially opposite inner and outer end portions respectively at the inner and outer peripheries of the annulus, the end portions of the openings at one periphery establishing material inlets and the end portions of the openings at the other periphery establishing material outlets; a relatively thin wire-like divider element extending circumferentially of the annulus at said one periphery and engaging the end portions of the spacers at said one periphery and axially intermediate said side members to circumferentially bridge the die opening end portions at said one periphery; and said end portions of the spacers at said one periphery being cut away to accommodate and provide

retaining means for removably receiving the divider element and retaining same in place in recessed relation to said end portions.

2. The invention defined in claim 1, in which: the retaining means includes a plurality of notches respectively in the end portions of the spacers at said one periphery, said notches being circumferentially aligned, and said divider element is received in and carried by said notches.

3. The invention defined in claim 2, in which: said notches open radially at said one periphery and said divider element is in the form of a snap ring removably received in said notches.

4. The invention defined in claim 1, in which: the retaining means includes a plurality of circumferentially directed apertures respectively in and adjacent to the end portions of the spacers at said one periphery, said apertures being circumferentially aligned, and said divider element has opposite ends and is of such length as to extend circumferentially as aforesaid, said element being threaded through said apertures and said opposite ends of the elements being brought together within one of said apertures.

5. The invention defined in claim 4, in which: said ends of the element are shaped to overlap and interfit within said one opening.

6. The invention defined in claim 1, in which: said retaining means and element are so constructed and arranged as to enable removal of said element from the annulus.

7. Die structure for a wafering machine, comprising: an annulus having inner and outer peripheries and including a pair of coaxially spaced apart ring-like side members and a plurality of uniformly circumferentially spaced apart generally radial spacers arranged between the side members and rigid therewith to provide a like plurality of die openings, each spacer and opening having radially opposite inner and outer end portions respectively at the inner and outer peripheries of the annulus, the end portions of the openings at one periphery establishing material inlets and the end portions of the openings at the other periphery establishing material outlets; a divider element extending circumferentially of the annulus at said one periphery and engaging the end portions of the spacers at said one periphery and axially intermediate said side members to circumferentially bridge the die opening end portions at said one periphery, said element being of limited radial dimension in the area of said one periphery and said end portions of the spacers at said one periphery being cut away to accommodate and provide retaining means for removably receiving the divider element and retaining same in place in recessed relation to said end portions.

8. Die structure for a wafering machine, comprising: means providing a row of die elements including a pair of transversely spaced apart side members and a plurality of spacers disposed between and rigidly secured to said members in uniformly spaced relation along said row to provide a like plurality of die openings, said spacers respectively having row-aligned material-inlet ends and opposite row-aligned material-outlet ends; a relatively thin wire-like divider element extending lengthwise of the row and laterally intermediate the side members and engaging the ends of the spacers at the inlet ends of the die openings to bridge and divide said inlet ends; and said inlet ends

of the spacers being cut away to accommodate and provide retaining means for removably receiving the divider element and retaining same in place in recessed relation to said inlet ends.

5 9. The invention defined in claim 8, in which: the retaining means includes notches respectively in said spacer ends and receiving said element.

10. The invention defined in claim 8, in which: the retaining means includes lengthwise-directed row-aligned apertures respectively in said spacer ends and through which said element is threaded.

11. Die structure for a wafering machine, comprising: a pair of spaced apart side members and a pair of spaced apart spacers rigidly disposed between the members to 15 provide a die opening in which opposed portions of the members afford a pair of walls and opposed portions of the spacers provide another pair of walls, said opening having a material-inlet end and a material-outlet end; a relatively thin wire-like divider element disposed intermediate the side members and extending between the spacers and bridging the opening at its inlet end; and said end portions of the spacers at said one periphery being cut away to accommodate and provide retaining means for removably receiving the divider element and retaining 20 same in place in recessed relation to said end portions.

12. The invention defined in claim 11, in which: the retaining means includes notches respectively in said spacers at said inlet end of the opening and receiving said element.

30 13. The invention defined in claim 11, in which: the retaining means includes aligned apertures respectively in said spacers at said inlet end of the opening and through which said element is threaded.

14. Die structure for a wafering machine, comprising: 35 a pair of spaced apart side members and a pair of spaced apart spacers rigidly disposed between the members to provide a die opening in which opposed portions of the members afford a pair of walls and opposed portions of the spacers provide another pair of walls, said opening having a material-inlet end and a material-outlet end; a divider element disposed intermediate the side members and extending between the spacers and bridging the opening at its inlet end, said element having a relatively small cross-sectional dimension in the direction of and relative to the length of the die opening from end to end of said opening; and said spacers being cut away at said inlet end of the opening to accommodate and provide retaining means for removably receiving the divider element and retaining same in place in recessed relation to said inlet ends.
